UNITED STATES PATENT OFFICE.

BURTON CHARLES VAN EMON, OF SAN FRANCISCO, CALIFORNIA, ASSIGNOR TO JAMES M. KOFORD, TRUSTEE, OF OAKLAND, CALIFORNIA.

ELEVATOR.

Application filed January 13, 1926. Serial No. 80,928.

My invention relates to the class of ram-elevators; and it concerns, primarily, structures in which, for any reason, the platform and the ram are freely separable.

In most elevator structures, the connection between the platform and the ram can be and is a permanent one, such, for example as a connection formed by bolting the ram head to the bottom of the platform. In such cases, the connection can be made as rigid and unyielding as may be necessary to insure movement without cramping or distortion stresses of any kind, and to maintain the desired horizontality of the platform.

There are other conditions, however, which require a freely separable connection between the ram and platform, as, for example the case of a platform which is intended to be moved from and clear of the ram, or to be individually manipulated in any manner, independently of the ram. Obviously, in such a case the problem involves a connection which is capable of being both readily made for elevating function and easily broken by intention, to enable the platform to be independently manipulated.

Such structures now find place in theatres where platforms are provided, which normally rest independently upon a stage floor and are fitted with power transmitting devices which permit their manipulation upon said floor in various directions, said platforms being also adapted to be elevated by rams to complete their movements as may be called for in the accomplishment of predetermined scenic effects.

In such cases, it is apparent that the connection between the ram and the platform must not only be a separable one, readily made and broken, but also that it shall be as rigid and unyielding as is possible in mechanical practise, in order to prevent distortion stress and to insure the horizontality of the platform; and this is the more important in the case of relatively large platforms such as in theatres, where a plurality of rams are required, because reliance must be placed upon the rigidity of the connection between the platform and rams to insure the travel of all the rams equally and as a unit. One object of my invention is, to provide a rigid separable connection between a platform and an elevating ram. This object is attained by entering the ram with a slip fit into a socket in the platform, to a depth and

with a fit necessary to insure lateral rigidity, and wholly withdrawing it from said socket.

Another object of my invention is to insure as perfect a fit of the ram into its socket as is mechanically possible. This object is reached by correspondingly tapering the socket and the entering head of the ram.

Still another object is to insure the ready release or withdrawal of the ram from the socket. This I attain by the novel disposition of a resilient member seated in the ram head, acting in conjunction with a pressure member associated with the socket.

Although my invention is adapted for and may be used with any platform under conditions requiring its separable connection with its elevating ram, I shall herein, for the sake of example, and as a disclosure of its utility, describe and illustrate it in connection with a theatre stage platform; but it is to be understood that I am not to be confined to such use, nor to the precise details of the mechanical structure of the connection between the rams and the platform, since changes may be made therein without departing from the spirit of my invention as defined by the claims hereunto appended.

In the accompanying drawings:

Fig. 1 is a vertical section, broken in length, showing a stage floor and a platform adapted for movement upon tracks in said floor, and showing, in vertical section, broken two rams and their separable socket connections with said platform.

Fig. 2 is a top plan view, broken, of Fig. 1.

Fig. 3 is a vertical section, enlarged, of said socket connection, the connection being fully made and ready for elevating function.

Fig. 4 is a vertical section showing the connection separated due to the functioning of the withdrawing spring.

1 indicates the structure, in general, of a stage floor. 2 indicates, in like manner, a platform, which by means of wheels 3 running on rails 4 is adapted for movement upon the floor 1. For the sake of simplicity I have shown only some gears 4' and have omitted, as forming no part of my invention, the rest of the power connections by which the movements of the platform upon the floor are effected, since my invention concerns only the elevation of the platform and the novel separable ram connections for

this purpose. In the platform 2, here shown as located at the properly selected and separated points, are the socket members 5. These are steel castings bolted to the structural beams of the platform. They are cup-shaped members and are inverted, their solid bottoms being uppermost and their mouths opening downwardly and exposed through the platform and the floor. The 10 rims of their mouths are preferably flared interiorly, as seen at 6, to afford ready entrance to their cavities.

Two rams are here shown. Each comprises a casing member 7 and a piston or 15 ram-member 8, fluid pressure being admitted to the casings by the pipes 9.

In order to insure accurate vertical movement of the rams 8, I steady them at three points, one at 10 at the foot, a second at the 20 stuffing boxes 11 at the top of the casings, and a third at the flared guide plates 12, bolted up under the stage floor in vertical alignment with the socket members 5 in the platform 2.

25 It will now be seen that assuming the platform 2 to be in proper position on the tracks of the floor 1, the ram member 8 rising, will enter the socket members 5 with a slip fit and when fully embedded therein 30 will elevate said platform. Also that on the reverse movement when the platform reaches and rests upon the floor tracks, the rams will withdraw wholly from the sockets. If now there be assumed as perfect line 35 movements of the rams and as true fittings of the rams in the sockets as are mechanically possible, it follows that according to the effective depth of the sockets a separable slip fit connection is provided which will 40 be practically laterally rigid during functioning and which will therefore preserve the horizontality of the platform; and where a plurality of rams are used such rigid connections will also insure equal and 45 unitary action of the rams, since the connections are unyielding; and as long as they preserve the normal planes of angularity between the platform and rams, one ram cannot get ahead of or lag behind the other.

50 I have thus far considered the socketed connection without regard to any special condition of its contacting surfaces, since both the bore of the socket and the entering head of the ram may each have its own 55 cross-sectional areas equal. But in practice, I find that if said socket bore and ram head be tapered, that is, formed with cross-sectional areas successively and uniformly decreasing upwardly, a better and more rigid joint or fit results, and one which is more easily separated. I have, accordingly, 60 in Figs. 3 and 4, particularly, with possibly some slight exaggeration, for the sake of illustration, shown this taper in both the 65 socket and the ram head.

In order to positively insure the release of the ram from the socket when the platform comes to rest upon the tracks of the stage floor, I associate with the connection a resilient member in the form of a spring 79 13. This spring is housed within a tube 14 which is firmly fixed within the head of the ram and is steadied below by a plate 15; it may also be further steadied between its foot and top. At its top it has screwed to 75 it a head flange 16 which is itself secured, as by means of the pins 17, Fig. 3, to the interior of the ram head. Into the head flange 16 is screwed a false ring 18 which confines a shouldered follower head 19 resting on top of the spring 13. In assembling these parts the spring 13 and its follower head 19 are inserted in the housing tube 14, and by means of a bolt, (not shown) temporarily passed through an opening 80 20 in the follower head 19 and down through the axis of the spring and screwed into the bottom steadyng plate 15 and then set up, the spring is initially condensed to admit the follower head 19 to the top of the tube 90 14 and permit the false ring 18 to be screwed in, to confine said head and spring. Then the bolt is removed.

Depending from the closed top of the 95 socket member 5 is a pressure pin 21.

When, as shown in Figs. 1 and 3, the ram has risen to and begins to enter its head into the socket member 5, the follower head 19 comes in contact with the pin 21 and as said ram continues to penetrate the socket, the follower head is forced down by said pin 21 thus condensing the spring, the limit of compression being reached when the ram head is home in the socket. Then the platform is elevated by the ram.

When, as is assumed in Fig. 4, the descent of the platform takes place until said platform rests on its rails, the spring 13, relieved of the weight of the platform, expands, and, pushing upon the pin 21, insures the withdrawal of the ram from the socket.

I claim:—

1. In an elevator, the combination of a platform having a socket; and a reciprocative ram adapted for a laterally rigid slip fit in said socket, said ram being adapted to wholly withdraw from said socket when the platform is lowered.

2. In an elevator, the combination of a platform having an upwardly tapering socket; and a reciprocative ram having an upwardly tapering head adapted for a laterally rigid slip fit in said socket, said ram being adapted to wholly withdraw its head from said socket when the platform is lowered.

3. In an elevator, the combination of a platform having a socket; a reciprocative ram adapted for a laterally rigid slip fit

in said socket; said ram being adapted to wholly withdraw from said socket when the platform is lowered; and supplemental means for positively initiating said withdrawal.

4. In an elevator, the combination of a platform having a socket; a reciprocative ram adapted for a laterally rigid slip fit in said socket, said ram being adapted to wholly withdraw from said socket when the platform is lowered and supplemental means carried by said socket and ram for positively initiating said withdrawal.

5. In an elevator, the combination of a platform having an upwardly tapering socket; a reciprocative ram having an upwardly tapering head adapted for a laterally rigid slip fit in said socket, said ram being adapted to wholly withdraw its head from said socket when the platform is lowered, and supplemental means carried by said socket and ram head for positively initiating said withdrawal.

6. In an elevator, the combination of a platform having a socket with a pressure pin fixed therein; a reciprocative ram having a head adapted for a laterally rigid slip

fit in said socket, said ram being adapted to wholly withdraw its head from said socket when the platform is lowered; and a spring housed in the ram head, adapted to be compressed by the socket pin under the weight of the platform and to be released for expansion when relieved of said weight.

7. In an elevator, the combination of a platform having a plurality of sockets; and a plurality of separate reciprocative elevating rams adapted for laterally rigid slip fits in said sockets, said rams being adapted to wholly withdraw from said sockets when the platform is lowered.

8. In an elevator, the combination of a platform having a plurality of sockets; a plurality of separate reciprocative elevating rams adapted for laterally rigid slip fits in said sockets, said rams being adapted to wholly withdraw from said sockets when the platform is lowered, and supplemental means associated with said sockets and rams for positively initiating said withdrawal.

In testimony whereof I have signed my name to this specification.

BURTON CHARLES VAN EMON.
